MULTIPLE POLE SWITCH

Frank H. Hesh, Chicago, Ill.

Application March 24, 1947, Serial No. 736,768

10 Claims. (Cl. 200—6)

1 The present invention relates to switches and more particularly to a multiple pole switch so constructed that any desired circuit controlled by the switch may be closed directly from the off or neutral position of the switch without moving the contactor of the switch through a progression of contact-making positions to reach the contacts for closing the desired circuit.

Multiple pole switches of the rotary type are commonly used at the present time for controlling a plurality of circuits from one switch, such for example as the circuits in lamps having bulbs of different wattage, each of which is hooked in a different circuit. It may be necessary to turn such a switch through several circuit-closing positions before the contacts controlling the circuit of the particular bulb or bulbs which it is desired to light have been closed. This results in unnecessary wear on the contacts and the moving elements of the switch and also leads to confusion and annoyance in the use of the switch because the user is not always certain how far the switch must be turned to close the desired circuit. The same thing is true when multiple pole switches of this type are used on equipment other than lamps.

The switch of the present invention may be moved directly from a neutral position to a position for closing any desired circuit in a multiple circuit arrangement so that it is not necessary to move the contactor of the switch step by step until a position is reached where the desired circuit is closed. As a result, control of equipment having a plurality of circuits may be simplified and wear on the switch is reduced to a minimum.

Accordingly, a primary object of the invention is the provision of a new and improved multiple pole switch for controlling a plurality of circuits in which the contactor of the switch may be moved directly from a neutral position to any one of a plurality of circuit closing positions for closing any one of a plurality of circuits.

Another object of the invention is the provision of a new and improved multiple pole switch which has a movable contactor, a push button or pivoted lever for moving the same to various circuit closing positions and resilient means for releasably holding the contactor in neutral position or in any one of the circuit closing positions, which resilient means engages the contactor and forms part of the circuit when the switch is moved to circuit closing position.

A more specific object of the invention is the provision of a new and improved multiple pole

2 switch which has a contactor movable by a push button connected thereto to various circuit closing positions and a plurality of resilient pins positioned normal to the contactor when the latter is in its neutral position, the pins engaging the contactor and being deflected thereby during movement of the contactor from neutral to circuit closing positions and vice versa, so that the resistance of the pins to deflection tends to releasably hold the contactor in neutral or in any one of the circuit closing positions.

A further object of the present invention is the provision of a new and improved multiple pole switch which is of extremely simple and inexpensive construction but which nevertheless is durable, foolproof, easy to operate, and wholly satisfactory in operation.

These and other objects of the invention will become apparent from the following description taken in conjunction with the accompanying drawings, in which:

Fig. 1 is a vertical sectional view of the switch of the present invention, with the contactor and contactor locking means shown in elevation;

Fig. 2 is a sectional view taken on line 2—2 of Fig. 1;

Fig. 3 is a sectional view of the switch of the present invention taken on the plane of the line 3—3 of Fig. 1 and with a phantom showing of the contactor in one circuit closing position;

Fig. 4 is a perspective view of the contactor locking means;

Fig. 5 is a vertical sectional view of another embodiment of the switch of the present invention with the contactor and contactor locking means shown in elevation and a phantom showing of the contactor in circuit closing position;

Fig. 6 is a sectional view of another modification of the switch of the present invention with the top cover removed and the contactor shown in full lines in neutral position and in phantom in one circuit closing position; and

Fig. 7 is a sectional view of a further modification of the invention showing a switch with the top cover removed and with the contactor shown in full lines in neutral position and in phantom in a circuit closing position.

In Figs. 1 to 3, the switch of the present invention is shown enclosed within a housing 10 comprising a generally cylindrical body 12 provided with a top cover piece 14. The body of the housing and the cover are preferably formed from an insulating plastic material or Bakelite and the cover is provided with peripheral threads so that it may be secured to the body by thread-

ing the same into the upper end of the body as indicated at 16 in Fig. 1 and thus it may be readily inserted and removed from position.

A four-pole switch has been shown for the purpose of illustration in Figs. 1 and 3, but it is to be understood that the principles of the invention may be applied to switches having a greater or fewer number of poles. The four poles shown in this switch each have a head forming a fixed contact 18 on one end, from which a stem projects to form a binding post 20. The posts 20 of the four contacts are inserted through openings in the side wall of the body member 12 with the fixed contacts 18 projecting inwardly of the housing, and they are secured in position by means of nuts 22 threaded on posts 20 and engaging the side wall of the housing.

This switch is connected into the different circuits which it is to control by connecting one terminal of one of the leads in each circuit to the binding posts 20. These terminals of the different leads are indicated at 24 in the drawing and they are shown engaged over the outer ends of the binding posts 20. They are held in position thereon by means of nuts 32 which press the terminals into firm engagement with the nuts 22 so that good electrical contact is secured between the fixed contacts 18 and the terminals.

Disposed within the housing 10 is a movable contactor element 34 which may be stamped from sheet metal having good electrical properties. The configuration of a contactor for a four-pole switch is shown in Fig. 3, but it is to be understood that the configuration will vary in accordance with the number of poles in the switch. As shown in Fig. 3, the periphery of a four-pole contactor has four biased convexly curved projections 36 equally spaced from each other by concave portions of the periphery 38 for a purpose which will be described in greater detail hereinafter.

A centrally located stem 40 projects upwardly from the contactor 34 through a slotted opening 42 in the cover 14 of the housing, and a push button 44 is threaded or otherwise suitably secured on the upper end of this stem, as shown in Fig. 1, in a position to be manipulated so that the contactor may be moved laterally to various positions. The number of slots in the slotted opening 42 conforms to the number of poles in the switch. Thus the opening 42 in the cover of a four-pole switch will be of cruciform shape as shown in Fig. 2. The stem 40 engages in the slots of the opening 42 when the push button 44 is moved laterally to any circuit closing position.

In order to prevent rotation of the contactor 34, the stem 40 is squared throughout the portion of its length which extends through the slotted opening 42 in the cover 14 and through a metal guide plate 26 which has a rectangular slot 28 conforming in length and width to one of the slots in the opening 42. The ends of this plate slide in diametrically opposite grooves 30 formed integrally with the cover so that the contactor assembly may be moved upwardly or downwardly from the position shown in Fig. 2, by pushing on the push button 44 and the stem 40 will be guided in the vertical slot of opening 42. When the contactor assembly is moved to the right or left from the position shown in Fig. 2, the stem 40 slides in the horizontal slot in the opening 42 and in the slot 28 in the guide plate 26. Thus it will be seen that the guide plate prevents rotation of the contactor assembly but

permits unimpeded movement of the same in any of the four circuit closing directions.

The contactor 34 is releasably held in neutral position out of engagement with the fixed contacts 18 or in any circuit closing position with a concave edge 38 in engagement with a fixed contact 18 by means of four equally spaced resilient pins 46 which extend vertically upwardly from a circular plate 54 fixed in the bottom of the housing 10. The plate 54 and four pins 46 are of conducting material and are connected to the line by means of a post 56 depending from the plate and extending through the bottom of the housing 10. A lead 58, connected to the line, is secured to this post in the same manner as the four leads 24 are connected to the fixed contacts 18 and thus the plate 54 with the four pins 46 is rigidly secured in position in the housing 10.

The four pins 46 are so located in plate 54 that their side edges will engage the apexes of the projections 36 when the contactor is in neutral position, as shown in Fig. 3, and the projections 36 extend outwardly just sufficiently so that the pins will not be stressed or deflected from their normal vertical position in the plate 54 when the contactor is in neutral position. As a result, the contactor is firmly held in this position but it can be moved by exerting a lateral force on the push button 44. Upon movement of the contactor 34 from the neutral position shown in Fig. 3 to the circuit closing position shown in phantom in the same figure, the two adjacent upper pins 46 riding on the opposite side projections 36 are first deflected outwardly by the projections and offer increasing resistance to movement of the contactor up to the point where the contactor has been moved far enough to bring opposite concave edges 38 into engagement with the pins 46. Thereafter, upon further movement of the contactor in the same direction the deflection of the pins riding on the concave edges will diminish so that the pins will tend to hold the contactor in engagement with a contact 18 and prevent movement of the contactor in a direction which would break the circuit.

Preferably, the projection of the fixed contacts 18 into the housing 10 is such that the contactor has to be moved somewhat beyond the point where the pins first engage the concave edges 38 to bring the contactor into engagement with the head of a fixed contact 18 and thus close one of the circuits controlled by the switch and in this new position the pins 46 project upwardly without deflection. Upon movement of the contactor in a direction opposite to that described above to break an established circuit, the two pins 46 engaging opposite concave edges 38 will be deflected by these edges and will resist this movement of the contactor until the contactor has been moved far enough to bring opposite convex projections 36 again into engagement with the pins, at which point the circuit will be broken. The stress exerted by the two upper pins on the convex projections 36 will force the contactor back to neutral position where it will be held as explained.

When the contactor is moved laterally in a circuit closing direction and the concave edge 38 engages with the head of its associated fixed contact 18, a circuit is completed through a terminal lead 24, contact 18, contactor 34, pins 46, plate 54, post 56, and lead 58. It will, of course, be understood that a circuit will be closed when the contactor is moved in each of the directions in which the guide slots in the slotted opening 42 allow it to be moved.

The form of the invention shown in Fig. 5 is generally similar to the preferred embodiment just described, except for the means used to actuate the contactor. The switch shown in this figure is provided with a housing 10 comprising a generally cylindrical body 12 and a top cover piece 60 which is provided with peripheral threads so that the cover may be secured in the body by screwing the same therein. This body is provided with four equally spaced fixed contacts 18 similar to those previously described and the terminal leads 24 are connected to these contacts as previously described. A circular plate 54 in which the pins 46 are mounted is secured in the bottom of the housing 10 by means of a post 56 to which a lead 58 from the line is connected in the manner explained for the corresponding parts of the embodiment previously described.

The contactor 34 is of the same configuration as the contactor used in the preferred form of switch except that its concave edges 58 are beveled as shown. It is provided with an actuating stem 62 which is secured in the central portion of the contactor. Intermediate its ends the stem 62 is pivotally secured upon a pin 64 extending diametrically of a slot formed between the meeting faces of a pair of semicylindrical members 66 which in assembled relation form a cylindrical journal for the stem 62 permitting the latter to be rocked in planes normal to each other. This journal is engaged in a cylindrical cavity formed in part in the bottom of cover 60 and in part in a retaining plug 68 engaged over the stem 62 and press fitted into a well in the bottom side of the top cover 60, so that the journal is free to rock in either direction on its axis and rocks the stem and contactor through a limited arc when it is so rocked. The slot through which the stem 62 projects extends axially of the cylindrical journal so that the stem is free to pivot upon the pin 64, as shown in phantom in Fig. 5, for engaging the contactor 34 with certain of the fixed contacts 18. However, movement of the stem 62 and hence of the contactor 34 is guided by four slots in the top cover arranged in a manner similar to the arrangement of the slots in the cover of the preferred form of switch.

The stem 62 is also provided with a spherical enlargement 70 of insulating material on its free upper end so that this end may be grasped between the thumb and forefinger when the switch is to be operated. Operation of this switch corresponds to the operation of the switch previously described except for the fact that the stem rocks with the journal 66 or pivots on the pin 64 instead of sliding laterally so that the contactor is swung or rocked into engagement with the fixed contacts 18 in the manner shown in phantom in Fig. 5. The pins 46 and contactor 34 co-operate in the same manner as the corresponding parts of the switch previously described to close the various circuits controlled by the switch.

In Fig. 6 the principles of the invention are shown incorporated in a six-pole switch. In this form of the invention six equally spaced contacts 18 are fixedly secured in the side wall of the housing 10, as shown, and are connected to terminal leads 24 in the various circuits controlled by the switch. The contactor locking means is provided with six resilient pins 46 instead of four, as in the previously described embodiments, and the contactor 74 is in the form of a disc which may be secured to the stem 76 of a push button as in the first embodiment. The top cover has six slots for guiding movement of the contactor

stem or actuator and thus guiding the movement of the contactor.

The operation of this switch is similar to the operation of those previously described. When the contactor 74 is moved from the neutral position shown in full lines in Fig. 6 to the position shown in phantom, at which one circuit is closed, the adjacent pins 46 and 46' are first deflected outwardly as the contactor passes between them and they resist this movement, but when the contactor 74 has moved laterally far enough to engage one of the poles 18 of the switch, its center point will have passed beyond the pins 46, 46' so that they are only slightly deflected from their normal position, if at all. This deflection causes the pins to press on the contactor 74 and to hold it in firm engagement with the fixed contacts 18 so that a force must be exerted on the contactor actuator to open any circuit once it has been closed.

The switch shown in Fig. 7 can be constructed in two different ways so that it can be used to control either four circuits, or eight circuits in which latter construction two circuits are simultaneously closed. As shown, the switch has eight contacts 18 fixed in the side wall of the housing 10 and each of these contacts is secured in position and connected to a terminal lead 78 in the manner previously described for the switch shown in Figs. 1 to 3. When the switch is to be used to control four circuits, the contactor locking means comprising the resilient pins 46 and circular plate 54 form no part of the circuit. Instead the two terminals of a circuit are connected to adjacent binding posts 26. For example, terminals 78 and 78' are connected to adjacent posts. When the contactor 34 is moved from the full line position shown in Fig. 7 to the position shown in phantom it bridges the two contacts to which the terminals 78 and 78' are connected so that one circuit is closed.

Various applications of the switches disclosed herein should immediately suggest themselves and while preferred embodiments of the invention have been shown and described, it will be apparent that numerous variations and modifications may be made without departing from the underlying principles of the invention. I, therefore, desire by the following claims to include within the scope of the invention all such variations and modifications by which substantially the results of my invention may be obtained through the use of substantially the same or equivalent means.

What I claim as new and desire to secure by Letters Patent of the United States is:

1. In a multiple pole switch, the combination comprising a housing, a series of contacts fixed in said housing, each of said contacts being connected to a separate circuit, a contactor in said housing movable in a plurality of directions from a neutral position directly to a position of engagement with any one of said contacts and vice versa for closing and opening the circuits connected to said contacts, a plurality of resilient pins in said housing, said pins being deflected by said contactor when the latter is moved from neutral position to circuit closing position and vice versa, and said contactor being releasably locked in neutral or in any of said circuit closing positions by the resistance of said pins to deflection, a stem secured to said contactor and adapted to be manipulated for moving said contactor into and out of engagement with said fixed contacts and guide means surrounding

said stem for confining movement thereof to the proper directions for moving said contactor into and out of engagement with said fixed contacts.

2. In a multiple pole switch, the combination comprising a housing, a series of contacts fixed in said housing, each of said contacts being connected to a separate circuit, a contactor in said housing movable in a plurality of directions from a neutral position directly to a position of engagement with any one of said contacts and vice versa for closing and opening the circuits connected to said contacts, a plurality of resilient pins in said housing, said pins being deflected by said contactor when the latter is moved from neutral position to circuit closing position and vice versa, and said contactor being releasably locked in neutral or in any of said circuit closing positions by the resistance of said pins to deflection, a stem secured to said contactor and slideable laterally with respect to said housing for moving said contactor into and out of engagement with said fixed contacts, a push button on said stem for manual operation thereof and guide means surrounding said stem for confining movement thereof to the proper directions for moving said contactor into and out of engagement with the fixed contacts.

3. In a multiple pole switch, the combination comprising a housing, a series of contacts fixed in said housing, each of said contacts being connected to a separate circuit, a contactor in said housing movable in a plurality of directions from a neutral position directly to a position of engagement with any one of said contacts and vice versa for closing and opening the circuits connected to said contacts, a plurality of resilient pins in said housing, said pins being deflected by said contactor when the latter is moved from neutral position to circuit closing position and vice versa, and said contactor being releasably locked in neutral or in any of said circuit closing positions by the resistance of said pins to deflection, a stem fixed at one end to said contactor and secured intermediate its ends for pivotal and rocking movement with respect to the housing, the free end of said stem being disposed for manual operation, and guide means surrounding said stem for confining movement thereof to the proper directions for moving said contactor into and out of engagement with said fixed contacts.

4. In a multiple pole switch, the combination comprising a housing, a series of contacts fixed in said housing, each of said contacts being connected to a circuit and adjacent contacts being connected to the same circuit in pairs, a contactor movable in a plurality of directions to a position of engagement with any one of said pairs of contacts connected to the same circuit and vice versa for closing and opening the circuits connected to the engaged pair of contacts, a plurality of resilient pins in said housing, said pins being deflected by said contactor when the latter is moved from neutral position to circuit closing position and vice versa, and said contactor being releasably locked in neutral or in any of said circuit closing positions by the resistance of said pins to deflection.

5. In a multiple pole switch, the combination comprising a housing, a series of contacts fixed in said housing, each of said contacts being connected to a separate circuit, a contactor movable in a plurality of directions to a position of engagement with two adjacent contacts and vice versa for closing and opening the two circuits connected to the engaged pair of contacts, a plurality of resilient pins in said housing, said pins

being deflected by said contactor when the latter is moved from neutral position to circuit closing positions and vice versa and said contactor being releasably locked in neutral or in any of said circuit closing positions by the resistance of said pins to deflection.

6. In a multiple pole switch, the combination comprising a housing, a series of contacts fixed in said housing, each of said contacts being connected to a separate circuit, a contactor in said housing having biased convex projections equally spaced by concave connecting edges, said contactor being laterally movable in a plurality of directions from a neutral position directly to positions for engaging any one of said concave edges with the fixed contact oppositely disposed thereto and vice versa for closing and opening the circuit connected to said contacts, means for moving said contactor and a plurality of pins positioned in said housing to engage said convex projections when said contactor is in neutral position, opposed pairs of said pins being deflected from their normal position by said contactor during initial movement of the same between neutral and circuit closing positions and vice versa, said contactor being releasably locked in neutral or in any of said circuit closing positions by the resistance of said pins to deflection.

7. In a multiple pole switch, the combination comprising a housing, a series of contacts fixed in said housing, each of said contacts being connected to a separate circuit, a contactor in said housing movable in a plurality of directions from a neutral position directly to a position of engagement with any one of said contacts and vice versa for closing and opening the circuits connected to the engaged contact, a plurality of resilient pins in said housing engaging said contactor and deflected thereby during movements of the contactor from neutral to circuit closing positions and vice versa, said contactor being releasably locked in neutral or in any of said circuit closing positions by the resistance of said pins to deflection, said pins and contactor forming part of the circuit through which current flow is conducted between one end of the line and the circuits connected to said fixed contacts.

8. In a switch, a body, a plurality of fixed contacts each adapted to be connected to a circuit, a contact member movable selectively into cooperative engagement with said fixed contacts, a plurality of cam faces associated with said contact member, resilient means fixed relative to said body adjacent one end and disposed to engage certain of said cam faces adjacent the opposite ends yieldingly to hold said contact member in open position, said opposite end of said resilient means engaging other of said cam faces when said contact member is moved to cooperative engagement with said fixed contacts for yieldingly holding the said member in said position.

9. In a switch, a body, a plurality of fixed contacts each adapted to be connected to a circuit, a contact member movable selectively into cooperative engagement with said fixed contacts, and means for yieldingly holding said contact member in open position or in cooperative engagement with said fixed contacts including a plurality of cam faces and a plurality of resilient means fixed adjacent one end and having their opposite ends disposed in the plane of said cam faces, said resilient means cooperating with certain of said cam faces to hold said contact member in open position and with other of said cam

faces to hold said contact member in cooperative engagement with said fixed contact.

10. In a switch, a body, a plurality of fixed contacts each adapted to be connected to a circuit, a contact member movable selectively to cooperative engagement with said fixed contacts, a plurality of cam faces formed on said contact member, resilient means fixed relative to said body member adjacent one end and disposed to engage certain of said cam faces adjacent the opposite end yieldingly to hold said contact member in open position, said opposite end of said resilient means engaging other of said cam faces when said contact member is moved to cooperative engagement with said fixed contacts for 15

10
yieldingly holding said member in position, said latter cam faces forming the contacts for engaging said fixed contacts.
